UNITED STATES PATENT OFFICE.

EDWARD C. PERRY, JR., OF WEST LYNN, MASSACHUSETTS, ASSIGNOR TO GENERAL ELECTRIC COMPANY, A CORPORATION OF NEW YORK.

ELASTIC-FLUID TURBINE.

1,156,549.

Specification of Letters Patent.

Patented Oct. 12, 1915.

Application filed April 9, 1914. Serial No. 830,805.

To all whom it may concern:

Be it known that I, EDWARD C. PERRY, Jr., a citizen of the United States, residing at West Lynn, county of Essex, State of Massachusetts, have invented certain new and useful Improvements in Elastic-Fluid Turbines, of which the following is a specification.

The present invention relates to steam turbines and particularly to a turbine designed to operate without the provision of any of the usual forms of speed governor or emergency shut-off means. Steam may be supplied to such turbines at a nearly constant pressure, as through a suitable reducing valve, and so long as the load remains substantially constant the speed will not vary to any considerable extent. Moreover, the turbine wheel may be so designed that the rotation loss will be high as compared with the shaft output and in this way the speed may be controlled for varying loads. In an arrangement of this character, if, due to the failure of the reducing valve for example, the bowl pressure should rise considerably the steam flow to the turbine wheel would increase and might cause an undesirable increase in the speed of the bucket wheel, particularly if it should occur at a time of relatively light load. According to the present invention I aim to provide an arrangement for taking care of such an emergency condition and one wherein, even if the bowl pressure should rise very high, the speed of the turbine wheel will not become unduly high.

As is known, the power obtained from steam furnished at a given pressure depends directly upon the exhaust pressure, that is the power depends upon the difference in pressure between the inlet and exhaust. In carrying out my invention I make use of this fact. To this end I provide the turbine casing in which the bucket wheel rotates with outlet openings of limited size and which bear a definite relation to the nozzle area. This outlet area will preferably be such that with normal bowl pressure the steam discharged from the turbine

wheel can pass from the wheel chamber with sufficient rapidity to keep the pressure therein at a value desired for normal operation. If now an increase in bowl pressure occurs which would ordinarily increase the speed of the wheel, the increased quantity of steam cannot escape through the exhaust opening until the pressure in the wheel chamber builds up to a higher value. The effect of this building up of pressure is to maintain the available energy and hence the steam velocity at a practically constant value. The increased flow of steam has, of course, the effect of somewhat increasing the speed of the wheel, but this tendency to increase is offset in a substantial measure by the rotation losses of the wheel revolving in a denser medium, said losses increasing very rapidly with increasing speed. Turbines of this type are in general adapted for very small units and are of practical utility only in those cases where extreme simplicity is of greater importance than economy in operation.

In addition to the above arrangement I may also cause the steam discharged from the turbine wheel casing to impinge against vanes carried by the turbine shaft. These vanes will be oppositely disposed to the buckets of the turbine so that the steam impinging against them will produce a retarding effect. This retarding effect will increase with both the speed of rotation and with the velocity of the steam flowing from the turbine wheel casing, and as this velocity increases with increase in the turbine casing pressure, it will be clear that the rotating vanes will function at the proper time to help maintain constant speed.

Referring to the drawings, Figure 1 is a section through a turbine illustrating an embodiment of my invention; Fig. 2 is a side view looking toward the left of Fig. 1 and with parts broken away; Fig. 3 is a sectional view showing a modification, and Fig. 4 is a detail development illustrating the arrangement of Fig. 3.

Referring first to Figs. 1 and 2, 5 is a shaft mounted in suitable bearings (not

shown) and carrying the turbine wheel 6. This turbine wheel will preferably be purposely designed to have a large rotation loss as compared to the shaft output, and to this end the diameter may be made large as compared to the nozzle area and shaft output, or the buckets may be made unusually high, or both. 7 is the turbine wheel casing having the removable closure 8 in which is arranged the nozzle 9 for directing motive fluid to the turbine wheel. Motive fluid is supplied to the nozzle by pipe 10 in which is arranged a suitable reducing valve 11, which will be set to reduce the motive fluid pressure down to the desired value. 12 is the exhaust conduit. Between the turbine wheel and the exhaust conduit is arranged suitable means for restricting the outflow from the casing. In the present instance I have shown the opening between the casing and exhaust as being closed by a plate 13 in which are arranged openings 14. The combined area of these openings bears a definite relation to the nozzle area and will be such that with normal pressure at the nozzle entrance the steam can flow from the casing with sufficient rapidity to keep the pressure in the casing and surrounding the wheel at a normal desired value. As is well known, the quantity of steam flowing through an orifice depends upon the difference in pressure upon the two sides thereof, and with normal initial pressure, the openings 14 will preferably be of such area as to require but a small pressure difference. Should the pressure at the nozzle entrance increase, as for example by failure of the reducing valve, then, as will be obvious, a much larger amount of steam will tend to flow. This increased amount cannot flow from the opening 14 at the pressure normally existing on the two sides thereof, and as a consequence the pressure of the wheel chamber will immediately build up. The effect of this building up of pressure is to maintain the available energy and hence the steam velocity at a practically constant value. The increased flow of steam still has the effect of somewhat increasing the speed of the wheel, but this tendency is offset in a substantial measure by the increased rotation losses of the wheel due to its revolving in a denser medium. The result will be to limit the speed of the turbine.

55 The arrangement shown in Figs. 3 and 4 is the same as that shown in Figs. 1 and 2, except that in addition thereto I provide an impeller wheel 15 having its vanes 16 arranged reversely to the buckets of the turbine wheel, as most clearly seen from Fig. 4. I have applied the same reference numerals to the corresponding parts in Figs. 3 and 4 as are used in Figs. 1 and 2. The retarding effect of this impeller wheel will

increase with increase in speed and also 65 with increase in the velocity of flow from the openings 14. From this it will be clear that in case the initial pressure on the nozzle should increase, thereby increasing the pressure in the turbine wheel casing, as already 70 explained, an increased velocity of flow from the openings 14 will result. This increased flow will coöperate with the impeller wheel in preventing rise in speed.

In accordance with the provisions of the 75 patent statutes, I have described the principle of operation of my invention, together with the apparatus which I now consider to represent the best embodiment thereof; but I desire to have it understood that the 80 apparatus shown is only illustrative, and that the invention can be carried out by other means.

What I claim as new and desire to secure by Letters Patent of the United States, is,— 85

1. The combination in a turbine, of a casing, a bucket wheel therein, a nozzle for supplying motive fluid to the wheel, an exhaust conduit, and means forming a restricted passage for conveying motive fluid 90 from the casing to the conduit, which passage is of such area as to maintain the pressure in the casing above that in the exhaust conduit.

2. The combination in a turbine, of a casing, a bucket wheel therein, a nozzle for supplying motive fluid to the wheel, and a restricted exhaust opening in the casing the area of which bears a definite relation to the nozzle area and is such that with normal admission pressure the pressure within the casing 100 will be slightly above that outside the same.

3. The combination in a turbine, of a casing, a bucket wheel therein, a nozzle for supplying motive fluid to the wheel, and an exhaust conduit, said casing having a series of openings therethrough forming a restricted passage for motive fluid from the casing to the exhaust conduit said openings being of 110 such area and bearing such relation to the nozzle area that with normal admission pressure the pressure in the casing is above that outside the same.

4. The combination in a turbine, of a casing, a shaft, a bucket wheel carried by the shaft within the casing, a nozzle for supplying motive fluid to the wheel, said casing having a restricted exhaust opening the area of which bears a definite relation to the 120 nozzle area, and an impeller wheel mounted on said shaft outside the casing and adjacent the exhaust opening, said impeller wheel having its vanes reversely arranged to the buckets of the turbine wheel.

125 5. The combination in a turbine, of a casing, a shaft projecting into the casing, a bucket wheel mounted on the shaft within

the casing, means for supplying motive fluid to the wheel, an exhaust conduit, said casing having a series of openings therethrough forming a restricted passage for 5 motive fluid from the casing to the exhaust conduit, and an impeller wheel mounted on said shaft outside the casing and adjacent said openings, the vanes of said impeller

wheel being reversely arranged to the buckets of the turbine wheel. 10

In witness whereof, I have hereunto set my hand this sixth day of April, 1914.
